WIDEBAND BUILT-IN RECEIVER ANTENNA

Winfield Rudolph Koch, Evesham Township,
Burlington County, N. J., assignor to Radio
Corporation of America, a corporation of Delaware

Application December 30, 1949, Serial No. 136,057

10 Claims. (Cl. 250—33.51)

1 The invention relates to antennas and it particularly pertains to antennas located within the receiver housings or within an auxiliary cabinet for television and frequency modulation reception, and which also can be oriented easily for optimum reception.

Many suggestions have been made for modifying the prior art antennas for such purposes. There are in general three requirements to be met. First, the antenna must be small and compact or of such configuration that it takes up but little of ordinarily available space. In other words, it must fit operatively into existing structure. Second, the antenna must be capable of wide band performance, that is, the reactance must remain low with variations in frequency, so that the signal voltage delivered to the receiver input terminals is high. Cone or fan type antennas are capable of wide band performance and also lend themselves to installation in conventional receiver cabinets. It has been suggested to meet these two requirements by an antenna in the form of thin sheet metal triangles fastened inside of the top of the cabinet, with the receiver input transmission line connected to adjacent corners of the two triangles. The directional pattern of this antenna is a figure-eight; and often not directed for maximum signal or minimum ghosts. To change the direction of these prior art antennas, the entire cabinet must be rotated, and viewing of the television image thus spoiled, not forgetting the possibility of setting up an unharmonious arrangement between the receiver and the other furnishings of the room. Hence, a third requirement of such an antenna is that its directivity be variable. Rotatable loops and dipole elements have been suggested for this purpose but obviously the space and cost requirements border on the unreasonable.

It is an object of the invention to provide a wide-frequency-band steerable antenna of simple and inexpensive construction for television and frequency modulation receivers overcoming all of the foregoing disadvantages.

It is another object of the invention to provide a connector for an antenna in accordance with the foregoing object for selectively interconnecting a television receiver, or frequency modulation receiver, to a built-in and an external antenna, without otherwise disturbing the connections thereto.

These and more specific objects of the invention which will appear as the specification progresses are attained in an antenna comprising a

2 plurality of wires radially arranged and having connections made by a selector device to allow the horizontal directivity of the antenna pattern to be changed in small steps while retaining the advantageous wide band performance otherwise provided.

Several embodiments of the invention will be described with reference to the accompanying drawing forming a part of the specification and

10 in which:

Fig. 1 is an arrangement of a steerable wide-band antenna according to the invention; and

Figs. 2a and 2b are illustrations of portions of alternate embodiments based on the arrangement shown in Fig. 1.

Referring to Fig. 1, there is shown an antenna arrangement which is intended for mounting in the interior of a cabinet, such as one used for housing a television or frequency modulation receiver, the confines of which are schematically indicated by the chain line 10. A plurality of conductors 12 are mounted in radial relationship to each other at a central point, and the adjacent ends are connected to terminals 14 of a switch 16, shown here as one of the conventional wafer type. Preferably an even number of conductors is employed, although conceivably any number can be used. For example, an arrangement of 23 conductors substantially equally spaced 20 will render an effective straight dipole of any two conductors extending in substantially opposite directions. Also, at least eight conductors are preferably used in order to provide effective electrical rotation in at least 45° steps, although of course a greater or smaller number of conductors may be used if finer change in directivity or only rough orientation is required. Switch 16 comprises two switch blades 18, each sufficiently wide to contact three adjacent switch terminals 14 at any given position of the switch arm, to which the conductors of a transmission line 20 leading to the receiver are connected.

In some cases conductors 12 will not be sufficiently long for best results if they stop at the 45 edges of the cabinet and hence end portions 12a can be run on down the sides of the cabinet as shown to improve the pickup and impedance match. It is not essential that they all be the same length or that the angles be exactly equal.

50 If desired (as shown in Fig. 2b), two or more wires may be connected to each switch point to provide wider band response and/or sharper directivity. For example, a switch having blades 55 connecting but two adjacent terminals, of eight such terminals having two radially arranged con-

ductors each, will afford a change of $22\frac{1}{2}^{\circ}$ directivity for each position of the switch. Conventional tuning and/or impedance matching elements may, of course, be interposed between the antenna and the transmission line if desired.

In place of switch 16 is shown in Fig. 1, conductors 12 may be terminated at a socket member 22, on the order of a tube socket, having equally spaced terminals, and transmission line 20 to the receiver may be connected to a complementary plug 24, having three pins on either side connected together so that when the receiver is placed in operation, the plug can be inserted and left in the position giving the best signal. The conventional octal socket is well suited for this purpose. It is necessary of course to remove the key from a conventional octal plug to permit rotation of the plug with respect to the socket. Referring to Fig. 2a, there is shown an arrangement of such a plug, which in this instance is a twelve pin plug designed for insertion in a conventional twelve pin cathode-ray tube socket. As previously mentioned, key 26 may be removed to permit rotation in the corresponding socket. However, it is also suggested that key 26 may be left intact and the aperture 28 of socket 22 be enlarged as shown by dotted line 20 as shown in Fig. 2b to permit rotation of plug 24 for selecting the position corresponding to optimum signal. In this manner plug 24 can be removed from socket 22 and plugged into another keyed socket to which a conventional outdoor antenna is connected. The cost of such an additional part is low, only two terminals being required, therefore it is considered a worthwhile feature to include 35 on television receivers, it being considered that the saving of time in installation will repay the cost of the additional parts.

In still another version of steerable wide-band antenna according to the invention, plug 24 is 40 constituted by two sectors 34, 35 as shown by dotted lines in Fig. 2a, having three pins each whereby the sectors may be adjusted independently of each other. In this manner not only finer steps of directivity change are available but also the resulting effective antenna becomes a wideband V antenna in the horizontal plane in which a greater pickup is obtained in the forward direction of the V than in the reverse direction. With an eight-pin socket such an arrangement will provide three times as many patterns as will be obtained with the previously described arrangement and a greater number will be realized for arrangements having a greater number of pins.

While the invention has been described in terms of specific embodiments, it is to be understood that other arrangements and modifications will be suggested by those skilled in the art without departing from the spirit and scope of the invention.

What is claimed is:

1. A compact steerable wideband antenna system, including a connector device having a given number of fixed contact members substantially 65 equally spaced around the circumference of a circle and a pair of variable contact making members arranged in fixed relationship to one another to contact groups of adjacent fixed contact members on opposite sides of said circle, the 70 number of contact members in each of said groups being greater than one and less than half of said given number, means to connect the conductors of a two conductor transmission line individually to said pair of contact making mem-

bers, and at least one elongated conductor having one end connected to each one of said fixed contact members and extending substantially radially away from said connector device substantially in a given plane with the remote ends of said conductors being free, successive ones of said conductors being connected to correspondingly successive ones of said fixed contact members.

2. A compact steerable wideband antenna system, including a connector device having a given number of fixed contact members substantially equally spaced around the circumference of a circle and a pair of contact making members arranged in fixed relationship with respect to each other to contact two groups of a lesser number of adjacent fixed contact members on opposite sides of said circle, said given number being greater than twice said lesser number and said lesser number being greater than one, means to connect the conductors of a two wire transmission line individually to said pair of contact making members, and at least one elongated conductor having one end connected to each one of said fixed contact members and extending substantially radially away from said connector device with the remote ends of said conductors being free, said elongated conductors being substantially equi-angularly spaced about said connector device and successive ones of said conductors being connected to correspondingly successive ones of said fixed contact members.

3. A compact steerable wideband antenna system as described in claim 2 wherein one of said groups of fixed contact members is diametrically opposite to said other group.

4. A compact steerable wideband antenna system as described in claim 2 wherein said elongated radially extending conductors are bent downwardly so as to require less space.

5. A compact steerable wideband antenna system, particularly for installation and operation within an instrument cabinet, including a connector device having an even number of fixed contact members equi-angularly spaced about the circumference of a circle and a pair of contact making members arranged in fixed relationship with respect to each other to contact two groups of a lesser number of adjacent fixed contact members on opposite sides of said circle, said lesser number being greater than one and said even number being greater than twice said lesser number, a two wire transmission line having the conductors thereof individually connected to said 55 pair of contact making members, and at least one elongated conductor having one end connected to each one of said fixed contact members and extending substantially radially away from said connector device with the remote ends of said conductors being free, successive ones of said conductors being connected to correspondingly successive ones of said fixed contact members.

6. A compact steerable wideband antenna system, particularly for installation and operation within an instrument cabinet and surrounding the instrument chassis, including a connector device having a given number of fixed contact members equi-angularly spaced about the circumference of a circle and a pair of contact making members arranged in fixed relationship to one another to contact groups of a lesser number of adjacent fixed contact numbers on opposite sides of said circle, said lesser number being greater than one and less than half of said given number, a two wire transmission line having the con-

ductors thereof individually connected to said pair of contact making members, and at least one elongated conductor having one end connected to each one of said fixed contact member and extending substantially radially away from said connector device with the remote ends of said conductors being free, said elongated conductors being substantially equi-angularly spaced about said connector device and successive ones of said conductors being connected to correspondingly successive ones of said fixed contact members.

7. A compact steerable wideband antenna system, including a switch having a given number of fixed contacts substantially equally spaced around the circumference of a circle and a pair of rotatable switch blades arranged in fixed relationship to one another to contact groups of adjacent fixed contacts on opposite sides of said circle, the number of contacts in each of said groups being greater than one and less than half of said given number, means to connect the conductors of a two conductor transmission line individually to said pair of switch blades, and at least one elongated conductor having one end connected to each one of said fixed contacts and extending substantially radially away from said switch substantially in a given plane, the remote ends of said conductors being free and bent out of said given plane in a given direction, successive ones of said conductors being connected to correspondingly successive ones of said fixed contacts.

8. A compact steerable wideband antenna system, particularly for installation and operation within an instrument cabinet and surrounding the instrument chassis, including a connector device comprising complementary plug and socket members, one of said members having a given number of contacts equi-angularly spaced about the circumference of a circle and the other of said members having two groups of a lesser number of adjacent complementary contacts connected together on opposite sides of said circle and spaced in the same manner as the first said contacts, said lesser number being greater than one and less than one-half of said given number, a two-wire transmission line having the conductors thereof individually connected to said groups of contacts, and at least one elongated conductor having one end connected to each one of the contacts of the first said member and extending substantially radially away from said connector device with the remote ends of said conductors being free, said elongated conductors being substantially equi-angularly spaced about said connector device and successive ones of said conductors being connected to correspondingly successive ones of said contacts.

9. A compact steerable wideband antenna system, particularly for installation and operation

within an instrument cabinet and surrounding the instrument chassis, including a connector device having a given number of fixed contact members equi-angularly spaced about the circumference of a circle and a pair of contact making members arranged in fixed relationship to one another to contact two groups of three adjacent fixed contact members on opposite sides of said circle said given number being greater than six, a two wire transmission line having the conductors thereof individually connected to said pair of contact making members, and at least one elongated conductor having one end connected to each one of said fixed contact members and extending substantially radially away in a given plane from said connector device with the remote ends of said conductors being free and bent out of said given plane, said elongated conductors being substantially equi-angularly spaced about said connector device and successive ones of said conductors being connected to correspondingly successive ones of said fixed contact members.

10. A compact steerable wideband antenna system, particularly for installation and operation within an instrument cabinet and surrounding the instrument chassis, including a connector device comprising a plug and a socket, said socket having eight contacts equi-angularly spaced about the circumference of a circle and said plug having two groups of three adjacent complementary contacts connected together on opposite sides, and a two-wire transmission line having the conductors thereof individually connected to said groups of contacts on said plug, and at least one elongated conductor having one end connected to each one of the contacts of the socket and extending substantially radially away from said connector device in a given plane with the remote ends of said conductors being free and bent out of said plane in a given direction, said elongated conductors being substantially equi-angularly spaced about said socket and successive ones of said conductors being connected to correspondingly successive ones of said contacts.
